[57] CLAIM

The ornamental design for tool handle, as shown and described.

DESCRIPTION

FIG. 1 is a perspective view of the tool handle showing my new design;

FIG. 2 is a front elevational view with the rear view being a mirror image thereof;

FIG. 3 is a top plan view thereof;

FIG. 4 is a bottom plan view thereof;

FIG. 5 is a left side elevational view thereof; and,

FIG. 6 is a right side elevational view thereof.

The broken line illustration in the drawing disclosure is for illustrative purposes only and forms no part of the claimed design.
